C. B. NAMOT

COMBINED LAMP STAND AND ASH TRAY

Filed July 2, 1927

INVENTOR

CHARLES B. NAMOT

BY

Yann Finkstein
ATTORNEY

UNITED STATES PATENT OFFICE.

CHARLES B. NAMIOT, OF NEW YORK, N. Y.

DESIGN FOR A COMBINED LAMP STAND AND ASH TRAY.

Application filed July 2, 1927. Serial No. 22,650. Term of patent 3½ years.

To all whom it may concern:

Be it known that CHARLES B. NAMIOT, a citizen of the United States, and resident of New York city, in the county of Kings and State of New York, has invented a new, original, and ornamental Design for Combined Lamp Stand and Ash Tray, of which the following is a specification, reference being had to the accompanying drawing, forming part thereof, in which the figure is a perspective view of a combined lamp stand and ash tray embodying my new design.

I claim:

The ornamental design for a combined lamp stand and ash tray as shown.

Dated New York, June 27th 1927.

CHAS. B. NAMIOT.
